Primary Examiner — Andrew T Nemeth*Assistant Examiner* — Gary N Chamberlin(74) *Attorney, Agent, or Firm* — GREENBERG TRAURIG LLP(57) **CLAIM**

The ornamental design for a display screen or portion thereof with a graphical user interface, as shown and described.

DESCRIPTION

FIG. 1 depicts a front view of a display screen or portion thereof with a graphical user interface showing a first embodiment of our design; and, FIG. 2 depicts a front view of a display screen or portion thereof with a graphical user interface showing a second embodiment of our design.

The broken lines illustrate portions of the graphical user interface and form no part of the claimed design.

1 Claim, 2 Drawing Sheets
